UNITED STATES PATENT OFFICE.

CHARLES C. PERCY, OF ROCHESTER, NEW YORK.

EXERCISING APPARATUS.

No. 806,565.

Specification of Letters Patent.

Patented Dec. 5, 1905.

Application filed November 4, 1904. Serial No. 231,415.

To all whom it may concern:

Be it known that I, CHARLES C. PERCY, a citizen of the United States, and a resident of Rochester, in the county of Monroe and State 5 of New York, have invented new and Improved Features of Construction for an Exercising Apparatus, of which the following is a full, clear, and exact description.

This invention relates to apparatus employed for strengthening the muscular system of a person by exercising different parts of the body therewith, and has for its object to provide novel details of construction for an apparatus of the character indicated which 10 are simple, readily adjusted for engagement with the upper portion of the person using the same, and which are safe as well as effective for strengthening the muscles of the user of the apparatus.

20 The invention consists in the novel construction and combination of parts, as is hereinafter described, and defined in the subjoined claims.

Reference is to be had to the accompanying 25 drawings, forming a part of this specification, in which similar characters of reference indicate corresponding parts in all the figures.

Figure 1 is a front perspective view of the suspended apparatus arranged for strengthening the muscles of the neck, arms, and shoulders of the user. Fig. 2 is a rear perspective view of the same as applied in Fig. 1. Fig. 3 is an enlarged rear view of the details of construction shown in Figs. 1 and 2. Fig. 4 is an enlarged side view of a chin-band employed. Fig. 5 is a perspective view of a portion of the apparatus, showing its application for strengthening the muscles of the hand and forearm of the user. Fig. 6 is an 30 enlarged side view of a novel hanger-ring, showing its connection with other details of the apparatus. Fig. 7 is an enlarged perspective view of a double-sheaved block, two flexible connections engaging separate sheaves in the block and leading in opposite directions, both ropes passing down from the sheaves through a grip-block, the end of one rope being knotted upon the other rope below the grip-block.

40 The invention is of a class in which means for partially or entirely suspending the person using the device is provided. To this end a suspending means having novel features is furnished as a detail of the invention and constructed as follows: Three hooks 10 are secured in an overhead stationary support. As

shown, the hooks 10 depend from the ceiling A of a room or the like and are evenly spaced apart. Two similar blocks 11 having a single pulley or sheave in each one are hung from the outermost hooks 10, and a double-sheaved pulley-block 11^a is suspended from the intermediate hook, as shown in Figs. 1, 2, 3, and 7. Two like ropes 12, which are thin, strong, and flexible, are respectively roven through the outermost pendent blocks 11, leaving portions thereof pendent, and from these blocks the remaining portions of the ropes 12 are extended toward and through the central block 11^a in opposite directions, respectively engaging with upper edges of the twin sheaves *a* therein, as is clearly shown in Fig. 7. The end portions 12^a of the ropes 12, which extend downward from the sheaves *a* in the block 11^a, pass loosely through a perforation in a grip-block 13, that may be 50 formed of wood having ovate form and one portion be secured on the other below the grip-block by a knot *b*, as shown in Figs. 3 and 7. The depending member 12^a, that extends below the grip-block 13, is afforded sufficient 55 length for effective service, and upon it at intervals other grip-blocks 13 are adjustably held in a desired position by the formation of a changeable knot *b* or the like in the rope, one below each grip-block, as appears in Figs. 3 and 5. The portions of the ropes 12 that hang from the pulley-blocks 11 at their outer sides are secured at their extremities upon hanger-rings 14 of novel construction, one ring being affixed upon a respective rope end 60 by a knot *b'*. Each of the similar hanger-rings 14 is preferably bent from a wire rod into an arched form, and at a proper distance from the ends eyes *c* are formed, the portions of the material that extend from the eyes each having a hook member *d*, bent outward and upward at the same side of the arched body of the ring. The eyes *c* on each hanger-ring 14 receive a straight spacing-bar *e*, which is secured therein, and upon one end of the bar a hook *e'* is formed which projects upward adjacent to one hook member *d* and in a plane at a right angle to the plane of said hook member *d*, as indicated in Fig. 6.

One detail of the invention comprises a chin-engaging band 15, that is preferably constructed mainly of leather, having on one side thereof a facing of wool or a soft pad of other material, as indicated at 15^a. The band 15 extends beyond the pad 15^a at each end of the latter 70 and on each extremity is provided with a band extension 15^b, that is therewith connected by

means of the eyepieces *g*, secured on the band proper at its ends. The extension-pieces 15^b are each adjustable for length, having the ends thereof passed through the eyes *g* and then 5 doubled together, the ends of the doubled portions engaging slideable buckles *h*, that by adjustment on the extension-pieces serve to lengthen or shorten them, as may be desired. The free extremities of the extension-pieces 10 15^b are respectively passed through the hanger-rings 14 and then doubled, so as to return their ends toward the slideable buckles *h*, and on said ends hooks *h'* are affixed that may be engaged with a cross-bar on a respective buckle 15 *h*, as is indicated at the right in Fig. 3.

It will be seen that if a patient wishes to strengthen the muscles of the neck and shoulders the band 15 may be placed beneath the chin and the person may apply draft strain 20 upon the chin-band by pulling upon the pendent rope 12^a. It is, however, not advisable to attempt this application of the chin-band unless the body is sustained in a manner which imposes part of the pull on the rope 12^a and 25 pendent rope members 12 upon the shoulders beneath the same, as will now be explained.

Two brace-bands 16, each having a ring *i* on the normally upper end, are detachably connected with respective hanger-rings 14 by 30 an engagement of the ring *i* thereon with an appropriate hook *e'*, as shown clearly in Fig. 3 at the left side thereof. The lower portions of the brace-bands 16 converge and are secured upon a triangular head-rest 16^a, which 35 extends between said portions of the bands, as best shown in Figs. 2 and 3. A strap 17 is affixed by one end on each brace-band 16 and thence may be extended toward a buckle *k* on the chin-band 15, these straps being preferably 40 adjustable for length, as indicated for one strap at the right in Fig. 3.

A shoulder-band 18 of sufficient length to extend across the back of the patient, then under the arms and up at the front, is connected with the hanger-rings 14, preferably by the following-described means. The shoulder-band may be in the form of a rope having a pliable covering 18^a, which is less in 45 length than the rope body and acts as a cushion for the band where it has contact with the person of the patient. At the center of the covering 18^a a strap 19 is secured which is buckled upon the converged lower ends of the brace-bands 16, as is clearly shown in 50 Figs. 2 and 3, thus adjustably connecting the shoulder-band with the brace-bands. Upon the end portions of the rope body of the shoulder-band 18 a plurality of rings 20 are secured in pairs that are suitably spaced apart, and, 55 as shown, each pair of rings is held changeably in place on the rope by a singly-tied knot *l*, and it will be obvious that by loosening the knot which holds any pair of rings at a certain point on the rope body 18 said knot may 60 be slipped along either way on the rope mem-

ber and then tightened, which will hold the rings at a selected point so as to lengthen or shorten the distance between said rings and the strap 19, as may be found desirable. There is a pair of rings 20 secured with a single 70 knot *l* at each end of the rope body of the shoulder-band 18, and these rings or other rings on the rope-end portions may be hooked upon the spaced hooks *d* on a respective hanger-ring 14, as shown in Fig. 6. It will 75 be seen that if corresponding pairs of rings on the end portions of the shoulder-band 18 are hooked upon respective hanger-rings 14 the weight sustained by the shoulder-band and the chin-band may be accurately divided, so that the proper draft strain will be applied upon the latter when the pendent rope member 12^a is pulled upon either by the patient or an attendant, the self-application of the 80 exercising apparatus for strengthening the neck and shoulder muscles being shown in Figs. 1 and 2.

In Fig. 5 the manner of using the apparatus to strengthen the muscles of the arms and fingers is shown. In this application the 90 hanger-rings 14 are engaged by one or more fingers of one hand at a time, and the pendent rope member 12^a is pulled upon with the other hand, an appropriate grip-block 13 being 95 grasped and more or less draft force thereto applied.

From the description hereinbefore given it will be apparent that the improved exercising apparatus is adapted for suspension from any stable object having sufficient height and which will receive the hooks 10; furthermore, that the apparatus is well adapted for convenient and safe use to strengthen the muscles of the upper portion of the human body, and that the tension applied to the muscular 100 system may be accurately graduated to suit the treatment appropriate for a patient, permitting the several details of the apparatus to be adjusted accurately for such a purpose.

Various minor changes may be made in details of the invention within its scope, and I claim all such as may fall within the intent of the claims.

Having thus described my invention, I claim as new and desire to secure by Letters Patent— 115

1. An exercising apparatus embodying two spaced suspended single-sheave blocks, a double-sheave block hung between the single blocks, two ropes each rovèn through one single-sheave block and passing through the 120 double-sheaved block in opposite directions, leaving end portions of the ropes hang from all the blocks, and means for connecting a human body with the pendent ropes adapted for putting draft strain thereon.

2. An exercising apparatus embodying two spaced suspended single-sheave blocks, a double-sheave block hung between the single blocks, two ropes each rovèn through one single-sheave block and passing through the 130

double-sheave block in opposite directions, leaving end portions of the ropes hang from all the blocks, means detachably connected with the ropes pendent from the single-sheave blocks and adapted for engagement with the chin and shoulders of a person, the remaining rope ends being pulled upon for causing draft strain on the chin and shoulders of said person.

3. In an apparatus of the character described, the suspending-tackle, comprising two spaced and suspended single-sheave pulley-blocks, a double-sheaved pulley-block hung between the other two blocks, two ropes each roven through a respective single-sheave block and passing through the double-sheave block in opposite directions engaging respective sheaves therein, end portions of the ropes hanging from each sheave, a hanger-ring pendent from the end of each rope hanging from a single-sheave block, each ring having an upturned hook thereon, a chin-engaging harness having straps engaged with members of the hanger-rings, and also having other straps that engage with the hooks on the rings.
- 25 4. In an apparatus of the character described, the suspending-tackle comprising two spaced and suspended single-sheave blocks, a double-sheaved block hung between the other blocks, two ropes each roven through a single-sheave block and passing through the double-sheaved block in opposite directions, end portions of said ropes depending from all the blocks, hanger-rings on ends of the ropes that depend from the single-sheave blocks, and a suspending-harness comprising a chin-band engaged with hooks on the hanger-rings, the remaining ends of the ropes that hang from the double-sheaved pulley when drawn down putting draft strain on the chin-band.
- 35 5. In an apparatus of the character described, the suspending-tackle comprising two spaced and suspended single-sheave blocks, a

double-sheaved block hung between the other blocks, two ropes each roven through a single-sheave block and passing through the double-sheaved block in opposite directions, end portions of said ropes depending from all the blocks, a hanger-ring on the end of each rope that hangs from a single-sheave block, said rings having upturned hooks thereon, and a suspending-harness coacting with the suspending-tackle, comprising a chin-band, a strap engaging at its ends with a hook on each end of the chin-band, a pair of brace-bands converged at their lower ends, a head-supporting band secured transversely on the brace-bands, a shoulder-band secured at its center on the converged ends of the brace-bands, all of said bands hanging from other hooks on the hanger-rings and coacting for putting draft strain on the engaged portions of a person when the depending ropes on the double-sheaved pulley are pulled upon.

6. In an exercising apparatus of the character described, the suspending-harness comprising a chin-band having adjusting-straps on its ends adapted for connection with the pendent ropes of a supporting-tackle, divergent brace-bands, adjusting-straps extended from the brace-bands to the chin-band, a head-band extended transversely between the brace-bands rearward of the chin-band, a shoulder-band connected near its center with the lower ends of the brace-bands, and rings at intervals changeably secured on the end portions of the shoulder-band for engagement with rings on a supporting-rope tackle.

In testimony whereof I have signed my name to this specification in the presence of two subscribing witnesses.

CHARLES C. PERCY.
